UNITED STATES PATENT OFFICE.

OLIVER H. ATTRIDGE, OF MONTGOMERY, ALABAMA, ASSIGNOR OF ONE-FOURTH TO WILLIAM N. COX, ONE-FOURTH TO CADWALDER W. BEALE, AND ONE-FOURTH TO FREDERICK G. BENNETT, ALL OF MONTGOMERY, ALABAMA.

WHEEL.

1,127,377.

Specification of Letters Patent.

Patented Feb. 2, 1915.

Application filed February 14, 1914. Serial No. 818,759.

To all whom it may concern:

Be it known that I, OLIVER H. ATTRIDGE, citizen of the United States, residing at Montgomery, in the county of Montgomery and State of Alabama, have invented certain new and useful Improvements in Wheels, of which the following is a specification.

This invention relates to resilient wheels and has for an object to provide a wheel of the inner pneumatic type having new and improved features of reliability of action, economy of manufacture and ease of operation.

15 A further object of the invention is to provide a hub with a surrounding floating structure, a pneumatic tube interposed between the hub and the floating structure, and rockers connecting the hub and floating structure to permit movement of the floating structure relative to the hub under impulse of ordinary use.

20 A further object of the invention is to provide improved means for locking the parts at will to eliminate the floating character of the outer member.

25 With these and other objects in view the invention comprises certain novel constructions, combinations and arrangement of parts as will be hereinafter more fully described and claimed.

30 In the drawings: Figure 1 is a view of the wheel in side elevation, one-fourth being shown with the hub plate removed disclosing the pneumatic tube and the adjacent parts. Fig. 2 is a diametrical sectional view taken on line 2—2 of Fig. 1. Fig. 3 is a sectional view of the hub taken on the same plane as Fig. 2 but enlarged. Fig. 4 is a perspective view of the nut locking ring. Fig. 5 is a view in side elevation of one of the rockers and associated parts. Fig. 6 is a sectional view through the rocker taken on line 6—6 of Fig. 5. Fig. 7 is a 35 view of one of the plates in side elevation with a bolt in section showing the means for permitting one part to float relative to the other. Fig. 8 is a sectional view taken on line 8—8 of Fig. 7.

40 Like characters of reference designate

corresponding parts throughout the several views.

The improved wheel which forms the subject matter of this application is adapted to operate with any style of axle, the configuration of the hub being varied to comply with the requirements of the axle. As shown in the drawing an axle 10 is employed with a hub 11 secured thereon in any approved manner as by the use of the nut 12. The hub 10 is provided with a peripheral flange 13 shown in the drawing as consisting of spaced members but it is to be understood that this form is immaterial to the present invention. About the hub 11 members 14 and 15 are secured in any approved manner as by the use of bolts 16. Upon the bolts 16 nuts 17 are employed with a ring 18 having notches 19 cut therein fitting upon said nuts. The ring fits upon the hub 11 and the hub cap 20 screws upon such hub and prevents the nuts 17 from loosening.

45 It will be noted, especially from Fig. 2 that the members 14 and 15 form a groove or furrow 21 in which is located a pneumatic tube 22. The pneumatic tube is inflated in any usual well known manner, a valve 23 being provided for that purpose.

Between the members 14 and 15 a floating structure is located consisting of spokes 24 and a central ring provided with a groove 25 bearing upon the tube. As thus far described the floating structure is free to move in any direction against the tension of the pneumatic tube 22, the members 14 and 15 being provided with shoulders 26 which will limit the movement of the floating structure.

50 As the drive is applied to the hub it is necessary to provide some means for transmitting such drive to the floating structure without preventing the creeping action thereof. To accomplish this purpose the floating structure is provided with a segmental opening 27 which may be surrounded by a casing 28 of some wear resisting material in case the material of the floating structure is not of sufficient hardness to withstand the wear. The opening 27

95 100

is provided at the side nearest the hub with a curved cam surface 29 and at the opposite side with a curved cam surface 30, both of which are arcs from the same center so that a rocker block 31 mounted within such opening is free to move slidably about such center. The block 31 is provided with a slot 32 within which is mounted a roller 33 with a bolt 34 extending through such roller so that the roller and bolt slide in such slot.

As shown in the drawing three of the rockers are provided this being found to be a desirable number although it is to be understood that the present invention is not limited to such number. It is also desirable to connect the members 14 and 15 at points in addition to those where they are connected by the bolts 34. For this purpose bolts 35 are employed which extend through openings 36 in the floating structure larger than the bolts to hold the members 14 and 15 in proper spaced relation but to permit the floating structure to move readily relative thereto. At other points, as for instance the points indicated at 37, holes are provided through the members 14 and 15 and through the floating structure so that pins may be inserted through such openings when it is desired to lock the floating structure in rigid relation to the hub. Such locking is found desirable or necessary when for instance the pneumatic tube for any reason becomes deflated or when the load is so heavy as to make it desirable to employ a rigid wheel rather than a pneumatic wheel. The periphery of the wheel itself may be completed in any approved manner as by employing a rim 38 and tire 39, these features being, however, the usual and ordinary cushion tire and rim.

It will be apparent that with the wheel constructed as shown at Figs. 1 and 2 the floating structure is free to move relative to the hub to the extent provided by the rocking of the blocks 31 in the openings 27 and the sliding of the rollers 33 in the slots 32. Assuming that one of these rocking structures is at the bottom of the wheel and subject to the load, the result will be to slide the roller 33 in the slot 32 toward the hub while the other two members will be subjected to a rocking movement to compensate for the movement of the floating structure relative to the hub. As the wheel rotates the position of the several parts will, of course, be changed, the several rockers being returned to normal position by the resiliency of the pneumatic tube which in fact carries the load.

By the employment of the rocker as shown particularly at Figs. 5 and 6 all lost motion, rattling and like objectionable features of wheels employing floating members

is obviated and eliminated while the pneumatic tube located between the hub and the periphery of the wheel is not subjected to wear or the cutting or fracturing of road use. By the employment of the parts as arranged all of the advantages of a pneumatic tire are secured while eliminating the objectionable rattle and other features of the inner pneumatic type of wheel.

It is obvious that any means may be employed for preventing dust and extraneous matter from entering between the plates 14 and 15 on the one hand and the floating structure on the other hand as by the use of the felt bands or rings 35'. By maintaining these felt bands saturated with oil the passage of dust is wholly prevented.

I claim:

1. The combination with a hub member having radial arms, and an outer member surrounding the hub and retained in position by the arms; of a compressible tube interposed between the members, a rocker mounted in the outer member and provided with a radial slot, and a bolt carried by the hub member and slideable within the slot of the rocker.

2. The combination with a hub member having a peripheral groove and arms extending beyond the groove, of an outer member having a complementary groove surrounding the hub and retained in position by the arms; a compressible member interposed between the hub member and the outer member and located in the groove; a rocker mounted in the outer member and provided with a slot; and a pintle carried by the hub member slideable within the slot of the rocker.

3. The combination with a hub member having a peripheral groove, of a floating structure surrounding the hub and provided with an inner complementary groove; a pneumatic member interposed between the members and located within the complementary grooves; rockers located in openings formed in one of the members and free to move, said rockers being provided with slots and bolts extending through said slots and through the hub member permitting the floating member to have a movement relative to the hub member.

4. The combination with a hub member having a peripheral groove, and a floating member surrounding the hub, one of said members having segmental openings; of a pneumatic tube interposed between the members, rockers loosely located in said openings and having radial slots, bolts extending through said slots and connected with the member which is not provided with said openings, and rollers on said bolts.

5. The combination with a hub having a peripheral bearing surface, of a floating

structure surrounding the hub and provided with a spaced complementary bearing surface; a resilient member interposed between the bearing surfaces of the hub and floating structure, said floating structure being provided at spaced points with segmental openings; segmental rockers located in the openings, said segmental rockers having the same radius but a shorter arc than the segmental

openings and provided with radial slots and 10 bolts extending through the radial slots and rigidly connected with the hub member.

In testimony whereof I affix my signature in presence of two witnesses.

OLIVER H. ATTRIDGE.
